UNITED STATES PATENT OFFICE

126,001

DESIGN FOR A DRESS

Germaine Monteil, New York, N. Y.

Application January 23, 1941, Serial No. 98,291

Term of patent 3½ years

To all whom it may concern:

Be it known that I, Germaine Monteil, a citizen of the United States, residing in New York city, in the county of New York and State of New York, have invented a new, original, and ornamental Design for a Dress, of which the following is a specification, reference being had to the accompanying drawing, forming part thereof.

The hood is integrally attached to the dress.

I claim:

The ornamental design for a dress, substantially as shown and described.

GERMAINE MONTEIL.
